UNITED STATES PATENT OFFICE.

GEORGE P. JACKSON, OF FLUSHING, NEW YORK, ASSIGNOR TO COMBUSTION ENGINEERING CORPORATION, OF NEW YORK, N. Y., A CORPORATION OF NEW YORK.

FURNACE AND BOILER.

Application filed January 16, 1925. Serial No. 2,748.

This invention relates to furnaces and boilers and is especially useful in connection with boiler furnaces fired by finely divided fuel, such as pulverized coal.

6 One of the objects of the invention is to provide a relatively small boiler of high capacity and to generally cheapen the cost of installations of this character. More specifically in this regard I propose a boiler 10 and boiler furnace arrangement taking up space largely vertically in comparison to the space occupied horizontally.

Another object of the invention has to do with the provision of an improved arrangement of furnace and boiler which can be accommodated in places having definite space limitations, without sacrifice in capacity.

Still another object of the invention has to do with a circulatory system comprised 20 of a plurality of groups of evaporating elements connected for circulation in such a way that a break in one group does not necessarily involve draining the other groups; and in which there is local circulation.

25 Another object of the invention is to protect the upright wall or walls of the throat of the furnace or combustion chamber.

The foregoing, together with such other objects as may hereinafter appear, or are 30 incident to my invention, are realized by a construction which I have illustrated in preferred form in the accompanying drawings, wherein

Fig. 1 is a vertical elevation thru a boiler 35 and furnace embodying my improvements;

Fig. 2 is a double section taken on the line 2-2 of Fig. 1, on enlarged scale, and

Fig. 3 is a fragmentary section illustrating modification of the invention.

40 Referring now to the drawings, it will be seen that A represents a combustion chamber, or furnace, having an outlet throat B at the upper part thereof, and pulverized coal admitting means such as a row of 45 burners C, located to one side of the outlet and adapted to discharge the fuel, preferably with carrying air, in a downward direction into the combustion chamber so that the fuel and flame stream describes a U-shaped course in its movement thru the combustion space. Part of the air is admitted 50 thru the burner castings and the balance of the air for combustion is admitted thru rows of inlets 7 in the front wall, the air delivered therethru being drawn thru com-

partments 8 within the furnace walls, whereby such air is preheated. The purpose of this will be hereinafter more fully pointed out.

Over the outlet are a plurality of superimposed groups or banks of boiler tubes, diagrammatically indicated as a, b, c. In each general group there are smaller groups 23, 24; 25, 26; 27, 28; respectively. The tubes of the general groups are each connected into headers and the headers in turn are connected together and to the combined water and steam drum 9 so that the groups are in the same general circulation altho having some local circulation.

It will be noted that these groups of tubes are of comparatively short length, the length of the bottom group of tubes being not materially greater than the horizontal length of the throat. The tubes are of shorter length 75 going upwardly. The waste products of combustion leave at the top of the boiler, any preferred arrangement of stack (not shown) being provided. The horizontal width of the group of tubes and the horizontal width of the combustion chamber proper and the throat is greater than the horizontal depth or length, as will appear on comparison of Figs. 1 and 2.

The general arrangement of the furnace 85 and groups of boiler sections is thus somewhat in the nature of a stack, slightly wider than deep horizontally. The installation thereof takes up a minimum of floor space. The U-shaped path of the flame provides the 90 needed length of flame travel for combustion.

To obtain high capacity, I provide evaporating elements which are largely subject to radiant heat. To this end, I arrange a 95 water screen D in the lower part of the combustion chamber. This screen is composed of tubes preferably connected into headers 9, of which there is preferably one for each tube. A second screen E is located in front 100 of the bridge wall 10 and is composed of tubes 11, the lower end of each of which is connected into a header 9. The upper ends of the tubes 11 connect with the header 12 from which a suitable number of pipes 13 105 lead to the steam space. The front ends of the tubes of the screen D connect into a header 14 and downcomers 15 connect this header with the water space. One or more screens F, preferably two, are located in the 110

throat B, the tubes thereof connecting into external headers in turn connected to the water space by downcomers 16 and to the steam space by upcomers 17.

5 Because of their location, these screens perform an extremely large amount of work and the boiler sections a, b, c, particularly the latter two, become substantially economizers. Hence the boiler comprised of 10 these groups may be comparatively small. It will be observed that the connections are such that there is local circulation and hence the boiler groups do not act as a "drag" on the screens and thus maximum efficiency of 15 the various evaporating elements is secured.

Furthermore, with the form of connection employed, drainage resulting from a break is reduced to a minimum.

The screens F function also to protect the 20 walls of the throat, and the screen E protects the bridge wall.

The tubes of the screen D are suitably spaced to permit the gravitating refuse particles to pass freely through the screen to 25 the floor, the particles remaining in individual form.

Since the evaporating elements tend to lower furnace temperature by absorption of heat, I introduce the major portion of the 30 air for combustion in a preheated state, to which end it is passed through the walls in the manner previously described. Thus maintenance of proper combustion is ensured.

35 The tubes 15 and 16 may have a common connection 18 with the water space.

In the arrangement of Fig. 3, the header 12 is connected to the header 20 of the boiler group a and the headers 21 of the throat 40 screens connect into the header 12. The tubes 15 lead from the header 22 of group a.

The straight rise of the gases eliminates dead pockets and has other advantages.

I claim:

45 1. In combination, a boiler furnace having an outlet throat in an upper part, means

for admitting finely divided fuel into the furnace in an upper part in a downward direction to one side of said outlet so that the fuel and flame stream describes a U-shaped 50 course through the furnace, a boiler consisting of three groups of boiler elements, a bottom and side wall screen forming one group, a throat screen forming the second group, and a series of banks of short tubes 55 constituting in effect an economizer section forming the third group, a steam and water drum, and separate connections between each group and boiler elements and the steam and water drum. 60

2. In combination, a boiler furnace having a combustion chamber with an outlet throat in an upper part thereof, a boiler having three groups of boiler elements, one group having a screen along an upright wall 65 of the combustion chamber, a second group having a screen along a wall of the throat, and another group having a bank of short tubes over the throat constituting in effect an economizer section, a steam and water 70 drum, and separate connections between each group of boiler elements and the steam and water drum.

3. In combination, a boiler furnace having an outlet throat in an upper part, means 75 for admitting finely divided fuel into the furnace in an upper part in a downward direction to one side of said outlet so that the fuel and flame stream describes a U-shaped course through the furnace, a boiler 80 consisting of three groups of boiler elements, a bottom and side wall screen forming one group, a throat screen comprising a plurality of rows of substantially upright tubes forming the second group, and a series of banks 85 of short tubes constituting in effect an economizer section forming the third group, each group having independent circulation.

In testimony whereof, I have hereunto signed my name.

GEORGE P. JACKSON.

CERTIFICATE OF CORRECTION.

Patent No. 1,714,600.

Granted May 28, 1929, to

GEORGE P. JACKSON.

It is hereby certified that error appears in the printed specification of the above numbered patent requiring correction as follows: Page 2, line 59, claim 1, for the word "and" first occurrence read "of"; and that the said Letters Patent should be read with this correction therein that the same may conform to the record of the case in the Patent Office.

Signed and sealed this 2nd day of July, A. D. 1929.
